DESIGN FOR A ROASTING EAR DISH OR THE LIKE

Joseph E. Gugenheim, Indianapolis, Ind.

Application April 7, 1938, Serial No. 76,349

Term of patent 7 years

To all whom it may concern:

Be it known that Joseph E. Gugenheim, a citizen of the United States, residing at Indianapolis, in the county of Marion and State of Indiana, has invented a new, original, and ornamental Design for a Roasting Ear Dish or the like, of which the following is a specification, reference being had to the accompanying drawing forming a part thereof.

Fig. 1 is a top plan view of a roasting ear dish, or the like, showing my design;
Fig. 2 is an end view of same;
Fig. 3 is a side elevation; and
Fig. 4 is a perspective view.

I claim:

The ornamental design for a roasting ear dish or the like, as shown.

JOSEPH E. GUGENHEIM.
